UNITED STATES PATENT OFFICE.

CARL S. HALLSTROM, OF MANKATO, MINNESOTA.

BRUSH.

1,173,265.

Specification of Letters Patent.

Patented Feb. 29, 1916.

Application filed March 23, 1914. Serial No. 826,695.

To all whom it may concern:

Be it known that I, CARL S. HALLSTROM, a citizen of the United States, residing at Mankato, in the county of Blue Earth and 5 State of Minnesota, have invented a new and useful Brush, of which the following is a specification.

This invention relates to fountain brushes, its principal object being to provide a brush 10 especially designed for use in cleaning vehicles, the back of the brush being so shaped as to be readily inserted into small spaces, such as those found between the spokes of wheels, etc.

15 A further object is to provide a fountain brush which can be readily attached to an ordinary hose and to which the bristles can be securely fastened without danger of being loosened by the jets of water issuing 20 from the back of the brush.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed without 30 departing from the spirit of the invention.

In the accompanying drawings the preferred form of the invention has been shown.

In said drawings:—Figure 1 is a vertical 35 longitudinal section through the brush. Fig. 2 is an enlarged section on line A—B Fig. 1.

Referring to the figures by characters of reference 1 designates a substantially semi-cylindrical brush back which is closed at one 40 end, as shown at 2 while its other end merges into a cylindrical stem or handle 3 the free end of which is preferably provided with a nipple or coupling 4 whereby 45 it can be connected to an ordinary hose. The back 1 is of course hollow and has openings 5 in the flat top thereof and in the arcuate bottom. The bottom openings receive the bristles 6 which are arranged in 50 strands and looped. These loops extend up

to the top of the back as shown in Fig. 2 so that they will be engaged and retained by the loops 7 of a wire or wires 8, these wire loops extending through the top openings 5. Outlet openings 9 are formed in 55 the arcuate bottom of the brush back at points between the bristle tufts and the water or other cleansing fluid supplied to the back of the brush is adapted to be discharged in jets from these openings 9. A 60 covering strip 10 of metal or any other desired material is secured in any preferred manner to the upper portion of the back 1 so as to conceal the exposed portions of the wires which engage the loops of the bristles. 65

In using the device herein described, the handle 3 is connected to a hose whereby water or other cleansing fluid may be supplied readily to the brush. The brush is then used as ordinarily and the bristles will 70 not only loosen and clear away any accumulations of dirt, but the jets of water discharged through the openings 9 will soften the dirt and wash it away.

Importance is attached to the fact that 75 the water is not discharged through the openings in which the bristles are mounted but is discharged through separate openings so that the force of the current issuing from the brush will not tend to loosen the bristles 80 and force them out of their positions in the brush.

It will be seen that the device is very simple and durable in construction, can be cheaply made, and efficiently used.

85

What is claimed is:—

A fountain brush including a substantially semi-cylindrical back constituting a liquid container for receiving liquid under pressure, a handle extending from and 90 opening into the back and constituting an inlet therefor, there being openings within the rounded wall of the back, looped bristles extending through said openings and terminating between the walls of the back, there 95 being openings in the top of the back, wires bearing upon said top and having loops extending through the openings therein and engaging the tufts of bristles to hold said bristles within their openings, there being

additional openings in the rounded wall of the back and between the tufts of bristles for the escape of liquid from the back, and a cover plate secured upon the top of the back and bearing downwardly on and concealing the fastening wires.

In testimony that I claim the foregoing

as my own, I have hereto affixed my signature in the presence of two witnesses.

CARL S. HALLSTROM.
